SOCK DRYING FORM

Albert L. Loutz, Los Angeles, Calif.

Application December 7, 1948, Serial No. 63,989

15 Claims. (Cl. 223—77)

1

My invention relates to forms upon which wet socks and more particularly wool socks are, after washing, adapted to be mounted in extended form to facilitate drying thereof. Such forms as heretofore made so hold the sock that when dried it is stretched out of its original shape and enlarged beyond its original size. In the drying process, particularly as with wool socks, there is considerable shrinkage. This results in imposing such tension on the heel and toe portions of the sock as to weaken and ultimately break the yarn threads, thereby shortening the usable life of the sock.

It is a purpose of my invention to provide a drying form for socks which has the transverse and longitudinal contour of the foot and leg of the wearer so that when a sock is mounted thereon it is held in that contour during the drying process, and thus such contour is preserved. In addition, the form is longitudinally contractible and extensible. In the contracted position it is of less length than the sock, and, hence, the sock when wet can be easily applied without subjecting the heel and toe portions of the sock to any distorting pull. While the form is in contracted position suitable clamps are employed to grip the sock at such points that upon moving the form to extended position to hold the sock in its original foot and leg length for drying, the heel and toe portions of the sock are secured against any stress or strain as a result of shrinkage, and, in consequence, there is no possibility of the threads of the heel or toe portions being weakened or broken as a result of the drying operation. Thus with my drying form, particularly a wool sock can be so held that when dried it has its original contour and size, and no part thereof is weakened as a result of the drying operation.

I will describe only one form of drying form for socks embodying my invention and will then point out the novel features thereof in claims.

In the accompanying drawings:

Fig. 1 is a view showing in vertical section one form of drying form for socks embodying my invention, and with a sock mounted thereon.

Fig. 2 is a top plan view taken on the line 2—2 of Fig. 1.

Fig. 3 is a horizontal sectional view taken on the line 3—3 of Fig. 1.

Fig. 4 is a vertical sectional view taken on the line 4—4 of Fig. 1.

Fig. 5 is a detail perspective view of one of the clamps of the form shown in Fig. 1.

Fig. 6 is a fragmentary perspective view of the upper end of the adjusting strap.

2

Fig. 7 is a plan view of one of the plates embodied in the form shown in Fig. 1.

Having specific reference to the drawings, my invention in its present embodiment comprises a body designated generally at B which may be made of plastic, sheet metal, or any other suitable material. This body has the transverse and longitudinal contour of the human foot and the lower portion of the leg so that its exterior contour is such that when a sock is mounted thereon it will be held in the same extended position as when on the human foot.

To allow free circulation of air through the form as well as through the sock, the body B is formed with perforations 15 and thus the drying of the sock is facilitated. The body is made in two longitudinal and identical parts which, when placed together at their confronting edges give the desired exterior contour. These body parts are secured one to the other by plates and screws as will be more fully described hereinafter.

The body B is made up of a main foot section 16 which transversely is of oval form, and tapered longitudinally from the heel end to the toe end 23 thereof. This section is formed integral with a heel section 17, and the latter in turn is integral with an angle and leg section 18. At the forward end of the foot section 16 is a toe section 19 which is rounded at its free end and tapered to have a sliding telescopic fit within the forward end of the foot section. At the upper end of the section 18 is a supplemental leg section 20 of inverted cup form which telescopically and slidably receives the upper end of such section. Preferably, both sections 18 and 20 are tapered as illustrated.

The two halves of the toe section 19 are secured one to the other by a plate 21 of oval form, and screws 22 extending through the toe section and into the edge of the plate. The two halves of the foot section 16 are secured one to the other by an oval shaped plate 23, and screws 24 extending through the halves and into the edge of the plate. The two halves of section 18 are secured one to the other by a lower plate 25 and screws 26, and an upper plate 27 and screws 28. This plate 27 abuts an annular shoulder 29 formed in the section 18 by reducing its diameter at this point. This shoulder also limits inward adjustment of the supplemental section 20.

For the purpose of extending and retracting the toe section 19 in respect to the foot section 16 so as to increase or decrease the overall length of the foot section, I employ a strap 30 made of plastic or metal which is freely movable through

slots 31 in the plates 23, 25, and 27, the forward end of the strap extending through the plate 21 where it is bent and riveted as at 32 to the forward side of the plate. The upper end portion of the strap extends through a slot 33 in the upper wall 34 of the section 20, and its projecting end is provided with a knob 35 adapted to be gripped for moving the strap longitudinally to extend and retract the toe section 19. This strap may be held in any longitudinal position of adjustment through a suitable latch 36 mounted on the wall 34 and having its latch bolt extended through any one of a series of openings 37 in the strap. Thus, the toe section 19 after an adjustment can be secured in such adjusted position.

It is desirable that the toe section 19 be held against turning on the foot section 16 for the dual purpose of preventing twisting of the strap, and twisting of the toe portion of a sock when mounted thereon. The means for securing the toe section 19 against turning is shown as comprising a pin 38 fixed on the inner side of the toe section, and a slot 39 formed in the foot section 16 and in which the pin is movable with the toe section so that in any longitudinal position of adjustment of the toe section on the foot section the toe section is held against turning.

An identical means is provided for securing the supplemental section 20 against turning in the leg section 18 and yet allowing axial adjustment thereof therein, and for the same purposes of preventing twisting of the adjusting strap 33 and the upper end of the leg portion of a sock when mounted thereon. Here the leg section 18 is formed with a longitudinal slot 40 while the section 20 has a pin 41 fixed to its inner side and movable in the slot.

For adjusting the section 20 axially in the section 18 and holding it in any position of adjustment I provide a shaft 42 rotatable in the wall 34 but confined against axial movement by a pair of annular flanges 43 fixed on the shaft at opposite sides of the wall. This shaft is screw-threaded as indicated at 44 in a collar 45 formed centrally in the plate 27, and its lower end has a cotter pin 46 extending therethrough to prevent displacement of the shaft from the plate. The upper and projecting end of the shaft 42 has a knurled head 47 by which the shaft can be manually turned to adjust the section 20 axially within the section 18.

To hold a sock on the form so that the heel and toe portions thereof are not stretched to a degree which might weaken or break the threads thereof, either under extended adjustment of the sections 19 and 20, or under shrinkage of the sock when drying, and to secure the sock in proper extended position thereon to maintain the original form of the sock, I provide a plurality of clamps preferably four in number and indicated at C1 to C4 respectively.

The clamps are identical in construction except as to shape of the bands, and each comprises a split band 48 the free ends of which are bent outwardly to form ears 49 to which the ends of a coiled contractile spring 50 are secured so as to construct the band. To receive the ovate band 48 of the clamp C1 a continuous groove 51 of U-form in cross section is provided in the toe section 19. Similarly, the band 48 for the clamp C2 is received in an annular and shouldered groove 52 in the body B at the junction of the sections 16 and 17, while the band 48 of the clamp C3 is received in an annular shouldered groove 53 at the junction of the heel and leg sections

17 and 18. Lastly, the band 48 of the clamp C4 is received in an annular and shouldered groove 54 in the section 20.

In the use of my form, before a wet sock S is applied thereto all clamps C1, C2, etc. are removed and the sections 19 and 20 are, by manipulation of the strap 30 and the shaft 42, retracted to their innermost positions thus reducing the overall length of the form to its minimum. 10 With the form so shortened application of the sock is facilitated and without subjecting it and particularly the toe and heel portions to any distorting pull. It will be understood, of course, that the open end of the sock is extended over 15 the toe section and then moved along the foot section and upwardly of the leg section until the entire sock is fitted on the form as illustrated.

Following such application of the sock, the several clamps C1, C2, etc. are applied in the respective grooves 51, 52, etc. thus firmly gripping the sock between the bands 48 and the form sections at the corresponding locations along its length. Now by pushing inwardly on the knob 35, after moving the latch 36 out of engagement 25 with the strap 30, the latter can be actuated to move the toe section 19 to an extended position in relation to the foot section 16, thus extending that portion of the sock between the top portion and the heel portion, to its full length on the form.

Since the sock is held by the clamps C1 and C2 during this operation no pull is exerted on the toe portion or the heel section of the sock, and thus the threads of these portions are not subjected to any damaging stresses even as a result of shrinkage when drying.

Upon rotation of the shaft 42 in the proper direction the supplemental section 20 can be projected from the section 18, and with the sock secured thereto by the clamp C4, the leg portion thereof is extended to its original length and so held for drying. Such sock extension imposes no strain on the heel portion thereof since the latter is held against pulling by the clamp C3.

Once the form sections are extended as described the form with the sock thereon may be suspended from any support by a hook 55 secured to the wall 34, and as will be clear, the perforations 15 will allow circulation of air through the sock to accelerate drying thereof.

From the foregoing described use of my form it will be manifest that a sock may be held in extended contour for drying and in its original size and shape without imposing any damaging stresses on the heel and toe portions thereof, and thus when dried the sock is not shrunk out of shape or size as with previous drying forms.

Although I have herein shown and described only one form of sock drying form embodying my invention, it is to be understood that various changes and modifications may be made therein without departing from the spirit of my invention and the spirit and scope of the appended claims.

65 What I claim is:

1. A sock drying form, including: a hollow body having a foot portion and a leg portion, both of which are axially extensible and retractible independently one of the other; means for moving and holding said portions into preselected positions of axial adjustment; and sock gripping means at spaced points along the length of said portions.

2. A sock drying form, including: a hollow body having a foot portion and a leg portion, both of

75

which are axially extensible and retractile independently one of the other; means for moving and holding said portions in preselected positions of axial adjustment; and sock gripping means on said body at points to hold the toe and heel parts of a sock against stretching or shrinking during drying, and yet effecting stretching of the other parts of the sock under extensibility of said portions.

3. A sock drying form, including: a hollow body having an axially extensible toe section and an axially extensible leg section; and means for adjustably extending said sections.

4. A sock drying form, including: a hollow body having an axially extensible toe section and an axially extensible leg section situated for operation at the free end of the leg section.

5. A sock drying form, including: a hollow body having a main foot section, a toe section telescoped on the main foot section, a heel section integral with the main foot section, a main leg section integral with the heel section, and a supplemental leg section telescoped on the main leg section; means for moving and holding the toe section in axial positions of adjustment on the main foot section; and means for moving and holding the supplemental section in axial positions of adjustment on the main leg section.

6. A sock drying form as embodied in claim 5, wherein both of said means are situated for operation from the free end of the supplemental section.

7. A sock drying form, including: a hollow body having a main foot section, a toe section telescoped on the main foot section, a heel section integral with the main foot section, a main leg section integral with the heel section, and a supplemental leg section telescoped on the main leg section; means for moving and holding the toe section in axial positions of adjustment on the main foot section; means for moving and holding the supplemental section in axial positions of adjustment on the main leg sections; sock gripping means on the toe section; a second sock gripping means at the junction of the main foot section and the heel section; a third sock gripping means at the junction of the heel section and the main leg section; and a fourth sock gripping means on the supplemental section.

8. A sock drying form, including: a hollow body having a foot portion and a leg portion, both of which are axially extensible and retractile independently one of the other; means for moving and holding said portions in preselected positions of axial adjustment; and sock gripping means at spaced points along the length of said portions, each of said means including a split band, and a spring for constricting the band.

9. A sock drying form as embodied in claim 7, wherein each of said sock gripping means comprises a groove in the corresponding section, and a band in the groove having means for constricting the same to clamp the sock material in the groove.

10. A sock drying form, including: a hollow and perforated body having the contour of the foot and leg, and made in two longitudinal parts; plates within said body secured to said parts for holding the latter in body form; said body having a main foot section, a main leg section, a toe section telescoped on the main foot section for longitudinal movement thereon; coacting means on said foot section and the toe section for securing the two sections against relative rotation; a supplemental leg section telescoped on the main leg section; coacting means on the last mentioned two sections for securing them against relative rotation; means for adjusting the toe section axially on the main foot section; and means for adjusting the supplemental section axially on the main leg section.

11. A sock drying form as embodied in claim 10, wherein said two adjusting means are situated for operation at the free end of the supplemental section.

12. A sock drying form as embodied in claim 11, wherein said two coacting means each comprise pin and slot connections between the respective sections.

13. A sock drying form as embodied in claim 10, wherein the adjusting means for the toe section includes a strap secured at one end to that plate in the toe section and movable through all of the other plates and the supplemental section, and a latch engaging the strap for holding it in any longitudinal position of adjustment.

14. A sock drying form, including a hollow body having an axially extensible toe section and an axially extensible leg section; means for adjustably extending said sections; and means for circumferentially holding a sock on said body so that under extension of the top section and the leg section the foot and leg portions of the sock can be extended without stretching the heel portion of the sock.

15. A sock drying form having a main foot section; a toe section axially adjustable on the main foot section; a main leg section; and a supplemental leg section axially adjustable on the main leg section; and means on certain of said sections for circumferentially gripping a sock so that when the toe section and the supplemental leg section are adjusted to extend said sections the foot and leg portions of the sock will be extended but stretching of the toe and heel portions of the sock will be prevented.
